by Wright, Blom, Dickey, Tracy
ATTYS.

UNITED STATES PATENT OFFICE.

GEORGE A. CONGDON, OF SOMERVILLE, MASSACHUSETTS.

SLUMBER-WAGON.

1,349,602.

Specification of Letters Patent. Patented Aug. 17, 1920.

Application filed December 26, 1919. Serial No. 347,513.

To all whom it may concern:

Be it known that I, GEORGE A. CONGDON, a citizen of the United States, residing at Somerville, in the county of Middlesex and State of Massachusetts, have invented new and useful Improvements in Slumber-Wagons, of which the following is a specification.

This invention has for its object to provide a portable structure in which an infant may sleep, embodying a crib and a chamber forming an enlarged inclosure over the head end portion of the crib, said chamber being adapted to be opened to permit the convenient insertion and removal of the occupant, and to afford a desirable protection when the structure is in use.

The invention consists in the improvements and combination hereinafter described and claimed.

Of the accompanying drawings forming a part of this specification,

Figure 1 is a perspective view of a slumber wagon embodying the invention, the shade hereinafter described being retracted.

Fig. 2 is a longitudinal section of the same, the shade being extended.

Fig. 3 is an enlarged fragmentary section on line 3—3 of Fig. 1.

Fig. 4 is a section on line 4—4 of Fig. 3.

Fig. 5 is a section on line 5—5 of Fig. 3.

The same reference characters indicate the same parts in all of the figures.

A structure embodying the invention includes a body formed as a crib having a fixed hood at one end, and a hood extension hinged to the fixed hood and forming therewith a chamber above the head end portion of the crib, the hood extension being displaceable to open the chamber, and being normally supported in its operative position by suitable stop means.

In the embodiment of the invention shown by the drawings, a box-like crib is provided, having a relatively low foot end member 12, a higher head end member 13, side members 14, of varying height conforming to the foot and head end members, and a top member 15 attached to the head member 13, and to the higher portions of the side members 14. The said side, head, and top

members form a fixed hood above the head end portion of the crib.

The hood extension, as here shown, comprises a top member 16, connected by hinges 17 with the member 15, and side members 18, attached to the top member 16, and arranged to overlap portions of the side members 14.

The top and side members of the hood extension define a front opening 19 in the extension, and the forward edges of the side members 18 are provided with shade-rod guides 20.

21 represents a shade-roller journaled in 65 bearings at the upper end of said opening. With said roller is suitably connected a flexible shade 22, having at its outer end a stiff rod 23, the opposite ends of which are adapted to slide in the guides 20. When 70 the shade is extended, so that its rod is in the position indicated by Fig. 2, the shade constitutes a closure for said opening.

It will now be seen that the fixed hood and the displaceable hood extension constitute a chamber over the head end portion of the crib, adapted to be opened by the displacement of the extension, as indicated by dotted lines in Fig. 2, the top member 16 of the extension being adapted to lie on the 80 top member 15 of the fixed hood when the hood extension is fully displaced. Provision is therefore made for the convenient placing and removal of the infant.

The shade-roller 21 may be any suitable 85 spring roller, adapted to automatically wind up the curtain, and any suitable means, such as the means ordinarily employed in connection with shade-rollers and their guides, may be employed for holding the shade-rod 90 23 at any point in its travel along the guides 20, so that the shade may be secured either fully or partly extended. When the shade is fully extended, as shown by Fig. 2, the portions of the chamber of which the shade 95 forms a part are closed above the body of the crib.

The hood extension may be supported in a partially displaced or raised position, to enlarge the chamber and permit the circulation of air under the forward portion of the hood extension, as indicated by dotted

lines in Fig. 2. The hood extension may be supported in the last-mentioned position by any suitable means, such as a dog 25, pivoted to the body of the crib, and adapted 5 to engage a notch 26 in one of the side members 18.

The guides 20 may be formed by parallel strips attached to and projecting from the inner sides of the side members 18, as best 10 shown by Figs. 3 and 5. The lower ends of said guides are preferably formed to bear on the upper edges of the side members 14 of the body, and thus limit the downward swinging movement of the hood extension.

15 To prevent the spreading of the side members 18, I connect the same by a transverse tie-rod 27.

The structure may be provided with any suitable running gear, here shown as embodied in an axle 28, and wheels 29, the axle being connected as by springs 30, with the bottom portion of the body. Legs or standards 31 may be attached to one end portion 25 of the body to coöperate with the wheels in supporting the body in a horizontal position. A resilient arm 33 may be attached to the bottom of the body and to the axle 28, the rear end of said arm being inclined downwardly at the rear of the axle, and 30 adapted to bear on a floor to prevent the head end of the structure from tipping too far downwardly. A suitable handle 34 may be provided at the foot end of the structure.

The body or crib may be upholstered, if 35 desired, and may be provided with a suitable spring bottom to support a mattress or bedding.

The forward ends of the side members 18 of the hood extension are preferably inclined, when said extension is in its operative position, so that the structure is adapted 40 to support a sheet of netting disposed upon the hood extension, and on the exposed foot end portion of the crib, to exclude insects from the chamber. The structure may be provided with suitable ventilating 45 openings 35, as shown by Fig. 1, and said openings may be protected by netting, if desired. A swinging cover 36 is shown 50 for closing one of the openings 35.

I claim:

1. In combination, a slumber-wagon body comprising a box-like crib having a relatively low foot end member, a higher head 55 end member, side members of varying height, conforming to the foot and head end members, and a top member attached to the head end member and to the higher portions of the side members, said side, head, 60 and top members forming a fixed hood, open at one side and located at the head end portion of the crib, and a displaceable hood-extension comprising a top member hinged to the top member of the fixed hood, side 65 members attached to the top member and

arranged to overlap portions of the side members, the top and side members of said extension being rigidly connected and defining a front opening in the extension, permitting access to the open side of the fixed 70 hood, and a movable closure for opening and closing said front opening, the said hood and extension constituting a chamber over the head end portion of the crib, adapted to be opened by the displacement of the 75 extension.

2. A slumber-wagon body embodying the combination specified by claim 1, the body being provided with means for engaging the extension, to support the latter in a 80 partly displaced position, to enlarge the chamber.

3. In combination, a slumber-wagon body comprising a box-like crib, having a relatively low foot end member, a higher head 85 end member, side members of varying height, conforming to the foot and head end members, and a top member attached to the head end member and to the higher portions of the side members, said side, 90 head, and top members forming a fixed hood, open at one side and located at the head end portion of the crib, and a displaceable hood-extension comprising a top member hinged to the top member of the fixed 95 hood, side members attached to the top member and arranged to overlap portions of the side members, the top and side members of said extension being rigidly connected and defining a front opening in the extension, permitting access to the open side 100 of the fixed hood, a shade roller journaled in bearings in the front opening of the extension, and a shade engaged with said roller, and adapted to be extended and retracted to open and close said opening.

4. In combination, a slumber wagon body, comprising a box-like crib having a relatively low foot end member, a higher head 110 end member, side members of varying height, conforming to the foot and head end members, and a top member attached to the head end member and to the higher portions of the side members, said side, head, and top members forming a fixed hood 115 above the head end portion of the crib, and a displaceable hood extension comprising a top member hinged to the top member of the body, side members attached to the top member and arranged to overlap portions 120 of the side members of the body, said top and side members defining a front opening in the extension, the forward edges of the side members being provided with shade-rod guides, a shade-roller journaled in bearings at the upper end of said opening, and a shade engaged with said roller and having a rod at its outer end adapted to slide in said guides, said shade, when extended, 125 constituting a closure for said opening, the 130

said hood and extension constituting a chamber over the head end portion of the crib, adapted to be opened by the displacement of the extension, stop means being provided for maintaining the hood extension in an operative position.

5. A slumber wagon embodying the com-

bination specified by claim 4, the side members of said hood extension being connected by a transverse tie-rod.

10

In testimony whereof I have affixed my signature.

GEORGE A. CONGDON.
